CLAIM

The ornamental design for a double-edged hid electronic ballast, as shown and described.

DESCRIPTION

FIG. 1 is a front perspective view of a double-edged hid electronic ballast showing my new design;

FIG. 2 is a rear perspective view thereof;

FIG. 3 is a front side elevational view thereof;

FIG. 4 is a top plan view thereof;

FIG. 5 is a rear side elevational view thereof;

FIG. 6 is a bottom plan view thereof;

FIG. 7 is a left side elevational view thereof; and,

FIG. 8 is a right side elevational view thereof.
